Application April 11, 1939, Serial No. 267,305
In Great Britain April 13, 1938

9 Claims. (Cl. 250—27)

The present invention relates to protective de-
vices for use in connection with high voltage elec-
trical apparatus such as cathode ray tube devices
as used for oscilloscope and television purposes.

5 It is the usual practice with cathode ray tube
oscilloscopes, where magnetic scanning (or de-
flection) and/or focusing for the beam is em-
ployed, to arrange the scanning (or deflection)
coils or the beam focusing coil to fit closely to
10 the outside of the envelope of the tube. The in-
side of the tube adjacent to the coils is usually
silvered or covered with a coating of some other
conducting material which comprises, or is con-
nected to, the final anode of the electron gun of
15 the cathode ray tube. There may be quite a
large capacity through the glass between the
conducting coating and the coils, for example,
a capacity of the order of 0.001 microfarad, and
in addition the potential of the coating may be,
20 for example, 50,000 volts positive with respect to
earth. Thus if a flash-over occurs between the
final anode and some other electrode at a lower
potential, or if the high tension supply is short-
circuited by any other occurrence, the potential
25 of the conducting coating may suddenly drop to
earth potential or nearly to earth potential. This
will momentarily cause the potential of the coils,
through the capacitative coupling, to drop to, say
50,000 volts negative with respect to earth, even
30 though the center point of the coils or the output
transformer feeding the scanning coils is earthed.
This is because the inductance of the coils pre-
sents a high impedance to earth for the sudden
surge. Such a potential across the coils, or part
35 of them, or across the output transformer, may
easily damage them and associated apparatus be-
sides making it dangerous to handle the coils,
etc.

It is one of the objects of the present invention
40 to provide means for substantially overcoming
this difficulty.

According to the present invention there is
provided means for protecting high voltage elec-
trical apparatus from the deleterious effects aris-
ing from a voltage flashover comprising a con-
ducting screen positioned between an electrode
45 of said apparatus which is maintained at a high
voltage and a component of said apparatus ad-
jacent said electrode, so that on the occurrence
50 of a voltage flashover from said electrode only
relatively small voltages are induced on said com-
ponent of said apparatus adjacent said electrode.
There is also a further difficulty due to the
55 fact that the leads from the lower potential elec-
trodes of the cathode ray tube to their respective

potential sources are usually fairly long and thus
have quite large inductive reactances to sudden
surges. If the inductances of the leads of the
lower potential electrodes are comparable with
or greater than the inductance of the high volt-
age lead, then the inductance potentiometer
5 formed during a flashover causes a large poten-
tial to be applied to the lower potential electrodes
with consequent damage to any associated ap-
paratus.

10 It is also an object of the present invention to
provide means for substantially overcoming this
further difficulty.

According to one feature of the present invention
there is provided a capacity connected to an
electrode of the apparatus which is maintained
at a relatively low voltage which capacity is large
compared with the capacity associated with the
high voltage electrode. The capacity connected
15 to the electrode of the apparatus which is main-
tained at a low voltage is preferably positioned
as close as possible to this electrode.

In order that the present invention may be
clearly understood and readily carried into effect
it will now be described with reference to the
25 drawing illustrating diagrammatically an em-
bodiment of the present invention in Fig. 1, and
showing in Fig. 2 one form of a suitable electro-
static shield for use in the invention.

In Fig. 1 is illustrated a cathode ray tube
2 such as is used for oscilloscopic purposes or
for the transmission or reception of television
pictures. The end wall of the envelope is pro-
vided with a suitable screen 31, such as a fluo-
rescent, mosaic or other screen according to the
35 purpose for which the tube is designed. On the
inside surface of the envelope of the cathode ray
tube is indicated at 3 a conducting coating which
may be connected to the final anode of the tube,
or as shown, the coating may comprise the final
40 anode. The electrode next to 3 is indicated at
4 and, as shown, may be the first anode as in the
usual construction. Normally these two elec-
trodes are connected to high potential sources,
for example, the potential applied to the final
45 anode 3 may be of the order of 50,000 volts and
the potential on the anode 4 may be about 2,000
volts. In order to deflect the cathode ray which
is produced by a thermionic cathode which is
conventionally illustrated in the tube, it is neces-
50 sary to fit suitable coils around the tube. In the
figure only one pair of deflecting coils 5 is shown
and the coils fit tightly around the glass of the
tube. Normally suitable deflecting currents are
55 applied to the scanning coils thus producing a

varying magnetic field which suitably deflects the electron beam over the end of the tube. In the known arrangements should the final anode flashover to the other electrodes or should the 5 50,000 volt supply be short-circuited for any reason, the scanning coils may momentarily take a potential of the order of 50,000 volts negative with respect to earth due to the comparatively large capacity (approximately 0.001 μ F.) between 10 the final anode 3 and the scanning coils 5. Naturally such a potential on the scanning coils is liable to damage any apparatus connected thereto, and is very dangerous to a person handling the apparatus.

15 According to the present invention a means of avoiding this difficulty is to insert an electrostatic screen 6 between the coils and the tube and to connect the screen to earth by means of a very low impedance connection. The screen 20 should be of metal cut into closely adjacent strips in such a way as to prevent the formation of eddy currents by the scanning field with consequent distortion of the field and loss of deflection amplitude. For example, the screen may 25 consist of a cylinder of metal foil cut into a number of circular strips, with a single connecting strip parallel to the axis of the cylinder joining all the rings and extending as an earth lead. For convenience of handling the foil 43 30 may be cut in a fish-bone shape and may be glued to a sheet of paper 41 or between sheets of paper as shown in Fig. 2, in such a way that the screen can be easily wrapped around the tube.

There is still a difficulty due to the inductance 35 of the leads between the potential sources and the various electrodes. In practice the leads form an inductive potential divider between the very high voltage source and earth when a flashover occurs. Should the impedance of the leads from 40 the electrode 4 be large then the proportion of the high voltage applied to electrode 4 during a flashover is large and damage to apparatus connected thereto, and possibly to the other electrodes and to apparatus connected to them due 45 to voltage flashover from the electrode 4 to these other electrodes, is inevitable.

This difficulty is overcome according to the invention by means of the circuit arrangement shown in Fig. 1. In the first place the condensers 8 and 9 which represent respectively the capacities between the high potential terminals 10 and 11 and earth, are arranged such that the capacity of condenser 9 is much larger than the capacity associated with the high voltage 50 terminal 11, represented by the condenser 8, the condenser 9 being positioned as close to the electrode 4 as possible. Thus when a flashover occurs the proportion of potential across the condenser 9 is small. Secondly an inductance 7, 55 which may comprise a long solenoidal winding, is connected between the high potential terminal 10 and the final anode 3. This has the effect of causing a large potential drop to occur across the inductance during a flashover and thus the 60 potential applied to the other electrodes is very much reduced. If however, the screen 6 is earthed, the comparatively large capacity between the screen 6 and the coating 3 acts as a 65 comparatively small impedance on the occurrence of a flashover and thus the effect of the inductance 7 is mitigated. To avoid this effect an inductance 12 is connected between the screen 70 and earth. However, the connection of an inductance between the screen and earth prevents 75 the screening action already referred to

for the purpose of preventing high potentials being applied to the apparatus associated with the coils. This difficulty is overcome by winding inductance coils 13, 14, 19 and 20 in the same direction and closely coupled with inductance 12 and by connecting winding 13 in series with one end of the scanning coil 5 and winding 14 in series with the other end of the coil 5, the scanning currents being applied to terminals 15 and 16. The coils 19 and 20 are connected similarly to the other scanning coil (not shown) and are fed with scanning currents through terminals 17 and 18. The coils 12, 13, 14, 19 and 20 are wound in such a way that a surge of current through screen 6 and coil 12 15 maintains the potential of the scanning coil 5 the same as that of the screen 6. It will be seen therefore, that the potentials at terminals 15, 16, 17 and 18 are then unaffected by a flash-over surge. The condition for maintaining the 20 potential of coil 5 the same as the potential of the screen 6 is that the inductance of coil 12 should be equal to the mutual inductance between the coil 12 and the other coils 13, 14, etc. One satisfactory way of winding the five coils 25 12, 13, 14, 19 and 20 is to wind a four wire (so-called "quad") screened cable in a solenoid form on a long former, the inside wires being used for coils 13, 14, 19 and 20 and the outer screening acting as coil 12. Alternatively, a double 30 wire screened cable can be wound in solenoid form with an insulated double wire cable wound closely over the screen cable. A further construction comprises a helically wound copper strip for coil 12 with four insulated wires wound 35 over the helix.

In the example of cathode ray tube shown the beam of electrons emanating from the cathode 37 is focused by the electrodes 33 and 35, first and second anodes 3 and 4, although it 40 will be understood that magnetic focusing may be employed for this purpose, either in conjunction with the magnetic means shown for deflecting the beam or in cases where electrostatic deflection of the beam is employed.

This invention is also not limited to the type of tube shown in Fig. 1 since it can be used in conjunction with any suitable type of tube where the necessity arises. For example, it can readily be employed with a television transmitting tube in which a photoelectric image is projected on to a mosaic screen and in which the image is focused on to the screen by magnetic means. The invention is, however, especially applicable to the so-called "projection type" of 55 cathode ray tube for reconstituting television signals in which the image is projected on to a viewing screen and in which very large operating voltages are used.

Having described our invention, what we 60 claim is:

1. A high voltage protection system comprising a cathode ray tube having beam forming means and an anode, means to supply high voltage to said anode, deflecting coils in cooperative 65 relationship with said anode, a conducting screen positioned between said anode and said deflecting coils, and inductor means connected to said conducting screen for allowing only relatively small voltages to be induced on said deflecting 70 coils upon the occurrence of a voltage flashover from said anode.

2. A high voltage protection system comprising a cathode ray tube having beam forming means and an electrode, means to supply high 75

voltage to said electrode, deflecting coils in co-operative relationship with said electrode, a conducting screen positioned between said electrode and said deflecting coils, and inductor means connected to said conducting screen for allowing only relatively small voltages to be induced on said deflecting coils upon the occurrence of a voltage flashover from said electrode.

5. A high voltage protection system comprising a cathode ray tube having beam forming means and an electrode, means to supply high voltage to said electrode, deflecting coils in co-operative relationship with said electrode, inductances connected in series with said deflecting coils, a conducting screen positioned between said electrode and said deflecting coils, and inductor means connected to said conducting screen for allowing only relatively small voltages to be induced on said deflecting coils upon the 10 occurrence of a voltage flashover from said electrode.

6. A high voltage protection system comprising a cathode ray tube having beam forming means and an electrode, means to supply high voltage to said electrode, deflecting coils in co-operative relationship with said electrode, inductances connected in series with said deflecting coils, a conducting screen positioned between said electrode and said deflecting coils, inductor 15 means connected to said conducting screen for allowing only relatively small voltages to be induced on said deflecting coils upon the occurrence of a voltage flashover from said electrode, and means to maintain said high voltage supply 20 and said inductor means at substantially the same potential.

7. A cathode ray tube system comprising a

cathode ray tube having a cathode, a modulating electrode, and beam forming electrodes including at least one anode, electromagnetic coils adjacent said anode for deflecting the formed beam, an electrostatic shield interposed between said coils and said anode, an inductor connected to said shield, a source of potential connected to said anode and means to maintain said inductor and said source at substantially the same potential.

8. A cathode ray tube system comprising a cathode ray tube having a cathode, a modulating electrode, and beam forming electrodes including at least one anode, electromagnetic coils adjacent said anode for deflecting the formed beam, an electrostatic shield interposed between said coils and said anode, an inductor connected to said shield, a source of potential connected to said anode and means to maintain said inductor and said source at substantially the same potential and inductance coils connected to said electromagnetic coils and coupled to said inductor.

9. A cathode ray tube system as claimed in claim 6 and wherein said inductance coils are coupled to each other.

10. A cathode ray tube system as claimed in claim 6 and wherein the inductance coils are coupled to each other and wherein the self-inductance of the inductor is equal to the mutual inductance between the inductor and the inductance coils.

11. A cathode ray tube system as claimed in claim 6 and wherein the inductance coils and the inductor are all wound in the same direction.
